SELECTIVE AUTOMATIC OVERLOAD
RELEASENicholas L. Etten, Waterloo, Iowa, and Adolph J.
Snow, Wilmette, Ill.

Application November 18, 1937, Serial No. 175,216

5 Claims. (Cl. 68—259)

This invention relates to a wringer roll pressure release and more particularly to an emergency or overload release mechanism for power operated types of wringers. While the invention 5 will be disclosed in connection with wringers and has many advantages making it particularly useful for wringer purposes, it has a broader application and may be incorporated in other types of machines employing two or more rolls for the 10 exertion of pressure.

One of the primary objectives of the invention is to provide means whereby the pressure on wringer rolls and the like may be substantially 15 instantaneously released in case of an emergency or other need, the means being of such character that the releasing may be accomplished automatically.

Another important object of the invention is to provide a wringer mechanism having an emergency release of such nature that it may be operated automatically or manually at the will of the 20 operator.

Another important object of the invention is to provide means whereby pressure on wringer 25 rolls and the like may be substantially instantaneously released in case of emergency or other need, the means being of such character that the releasing mechanism is actuated by a certain movement of the pressure rolls.

30 A further object of the invention is to provide an overload release of such design that it may be rendered inoperative at will.

Another important object of the invention is to provide a release mechanism for pressure rolls 35 which may be operated by manual means, or by automatic overload means, the mechanism being of such design that the automatic releasing means may be rendered inoperative to permit operation of the device under heavy loads.

40 Another object is to provide an emergency releasing means for pressure rolls which is simple in construction, dependable in operation and economical in manufacture.

In the manufacture of wringers, and particularly power operated wringers, it has been customary to provide emergency release mechanisms 45 as a safety measure, since the pressure exerted by the wringer rolls is great enough to be dangerous to the operator. Ordinarily these emergency release mechanisms take the form of a manual control, such as, for example, a bar, knob or push button, and these may be manually actuated by the operator to release the pressure rolls. It should be noted, however, that 50 these means require manual operation and in

case of an emergency, as, for example, in the event that the operator's hand is caught by the wringer rolls, the manual operation must be accomplished almost instantaneously if the pressure is to be released before the operator has been 5 seriously injured. It should also be taken into consideration that at the time of such emergency the operator will, of course, be in pain and may lack the presence of mind to operate any manual release mechanism. In this connection it should 10 also be noted that the operator may be unfamiliar with the release mechanism on the machine and, therefore, may be unable to operate it, or a child may be operating the machine without the knowledge of the existence or operation 15 of the release mechanism. In the event that the operator's hand should become caught between the wringer rolls, it may happen that in a panic stricken attempt to withdraw the one hand the other hand may also be caught between the rolls 20 and thus prevent, or at least greatly hinder the operation of any form of a manual release.

In view of these facts many automatic types of release have been constructed, but as a rule these have met with little success for several reasons. 25 Certain types of automatic release have been so adjusted that they would automatically release the pressure upon the rolls in the event that objects of greater than the minimum thickness should pass between the rolls. These have a distinct disadvantage in that at times it becomes necessary to wring heavy goods, as, for example, blankets or rugs, and if the automatic releasing mechanism is so adjusted that it will release in the event that the operator's hand should become 35 caught between the rolls, it will be found that the wringer is not capable of handling any goods except those of a minimum thickness. Other forms of automatic release mechanisms have attempted to place releasing bars in close proximity to the 40 rolls in such a manner that bulky articles passing through the rolls will strike and actuate the release bars. This type of release has also proven of little value for the reasons outlined above. In the present invention these and other difficulties are overcome, and the aforementioned objects are accomplished as will be seen by reference to the drawings in which a preferred embodiment of the invention has been shown.

Fig. 1 is a side elevation of a typical wringer 50 mechanism constructed in accordance with the principles of this invention and having certain parts broken away;

Fig. 2 is a detail sectional view taken on the line II—II of Fig. 1;

Fig. 3 is a detail plan sectional view taken on the line III—III of Fig. 1;

Fig. 4 is a longitudinal sectional view of the wringer showing the parts thereof in their operative position;

Fig. 5 is a detail sectional view of the release control knob and is taken on line V—V of Fig. 8;

Fig. 6 is a longitudinal sectional view of the wringer similar to Fig. 4, but showing the parts 10 in their released position;

Fig. 7 is a detail sectional view taken on the line VII—VII of Fig. 4;

Fig. 8 is a detail sectional view taken on the line VIII—VIII of Fig. 4; and

Fig. 9 is a detail bottom plan section taken on the line IX—IX of Fig. 8.

In the illustrated embodiment of the invention the wringer frame is composed of a bottom channel 10 carrying upright end channels 11 and 12. The upright end channel 11 is affixed to the bottom channel 10 at the extreme left end of the latter, as viewed in the drawings, and is secured thereto by means of rivets 13 while channel frame 12 is secured to the right hand end of bottom channel 10 by rivets 14. A pair of guide rails 15 and 16 are carried within the upright channel 11 and are secured thereto by means of rivets 17. These guide rails 15 and 16 are provided with inturned portions 19 and 20 adapted to be received 30 in notches in the bearing members 21 and 22 and serve to guide the bearing members during vertical sliding movements of the latter. A pair of similar guide rails 23 are carried within the channel 12 and are secured thereto by means of rivets 24. The guide rails 23 include inturned portions 25 which act as vertical guides for bearings 26 and 27 at the right-hand end of the wringer. A lower wringer roll 30 is journaled in the bearings 22 and 27, while an upper wringer roll 31 is journaled in the bearings 21 and 26. The shaft 32 of the lower roll 30 extends beyond the bearing 22 and is adapted to engage a driving means of any customary form. A pair of drain boards 35 are positioned on either side of the lower wringer roll 30 and are secured to the end channels 11 and 12 in any suitable manner, as, for example, by screws 36. The bottom channel 10 is perforated, as shown at 37, to allow water falling from the rolls 30 and 31 to pass therethrough and 50 to deflect to either side of the machine by means of a flipper 38 mounted on brackets 39 and 40 by pivot pins 41. The brackets 39 and 40 are secured to the bottom channel 10 by any suitable means, as, for example, by rivets 42. The bracket 55 40 carries a supporting bracket 43 and the end channel 11 carries a bracket portion 44. These brackets 43 and 44 may be bolted to other mechanism (not shown) as, for example, to the customary power head, in such a manner as to support the wringer frame. A pair of adjusting screws 45 are positioned beneath the bearings 22 and 27 to adjust the elevation thereof and may be locked in a predetermined position by the nuts 46.

65 A top channel 48 carries a pressure adjusting cap 49 positioned directly over the rolls 30 and 31. This pressure adjusting cap 49 includes a hub portion 50 and has a tension adjusting plate 51 secured thereto by a screw 52. A washer 53 70 spaces the plate 51 from the channel 48 and facilitates the rotation of the plate 51 by means of the adjusting cap 49. The tension adjusting plate 51 is provided with a plurality of notches 54 of varying height. These notches 54 are 75 adapted to engage a leaf spring 55 extending from

the bearing member 21 to the bearing member 26 and secured to these bearings by means of plates 56 and 57 riveted to the bearings and releasably secured over the ends of spring 55. By rotating the adjusting cap 49, the plate 51 will be rotated 5 and the leaf spring 55 will be engaged by a notch of predetermined height in the plate 51. It will be seen that the height of the notch 54 will determine the degree of flexing of the spring 55 and, consequently, the effective operating pressure between the rolls 30 and 31.

An anchor pin 58 is riveted in the top channel 48 and is adapted to engage a notch 59 in the vertical end channel 12. A cross pin 60 is riveted in the opposite walls of the end channel 11 and a reset link 61 is pivoted thereon. A reset handle 62 is mounted on a pivot pin 63 riveted in the opposite walls of the top channel 48. This reset handle 62 carries a pair of ears 64 pivotally connected to the reset link 61 by a pin 65. A latch 66 is pivotally mounted on the latch pivot 67 which may be riveted in the opposite walls 48^a and 48^b of the top channel 48. The latch 66 carries ear portions 68 and one of these may be punched, as at 69, to accommodate one of the 25 ends of a spring 70. The spring 70 is preferably supported intermediate its ends on the latch pivot 67 and at its opposite end is anchored on a cross pin 71. The spring 70 normally tends to urge the latch 66 in a clockwise direction about pivot 67, 30 as viewed in Figs. 1, 4 and 6 of the drawings, and so as to engage a latch pin 72 which is preferably riveted between two down-turned flanges 73 on the reset handle 62. A spacer 74 is carried by the latch pivot 67 and by a cross pin 75 and a pair of 35 retaining links 76 are carried by the cross pin 75 and are adapted to engage certain other mechanisms (not shown) in such a manner as to urge the top channel and parts mounted thereon to the right as viewed in the drawings at the time the 40 latch 66 releases the latch pin 72. It will be seen that this action is effective to release the anchor pin 58 from the notch 59.

A pair of latch trip arms 77 and 78 are also pivotally mounted intermediate their ends upon 45 the pin 63 and are connected at one end of each by a latch trip bracket 79 secured in place by means of rivets 80. At the opposite ends of the latch trip arms end portions 81 and 82 engage notches 83 in the ear portions 68 of the latch 66. 50 It will be seen from this construction that any upward force exerted upon the release bar bracket 79 will move the end portions 82 of the latch trip arms 78 downwardly against the ear portions 68 of the latch 66 and cause the latch 66 to pivot 55 about the pin 67 in a counterclockwise direction as viewed in the drawings. This pivotal movement against the action of the spring 70 will be effective to release the latch pin 72 carried by the reset handle 62 and allow the reset handle 62 to 60 swing into the position shown in Fig. 6. This action breaks the retaining connection as established between the reset handle 62, pin 65, link 61 and the pin 60 and permits the entire top channel 48 and all parts associated therewith to rise. 65 As will be evident from the examination of Fig. 6 the anchor pin 58 also releases from the notch 59 and the plate 51 rises from the leaf spring 55. In this position the pressure between the rolls 30 and 31 is completely released and the upper roll 70 75 31 is held in the position shown by gravity only.

A pair of release bars 84 and 85 are carried by release bar brackets 86 and 87 at one end and by somewhat similar brackets 88 and 89 at the opposite end. The brackets 86 and 87 are chan- 75

nel shape in cross section and each includes a pair of operating end portions 90 and 91 extending through slots 92 in the opposite walls 48^a and 48^b of the top channel 48. As will be seen in Fig. 7 the slots 92 are sufficiently long to permit the end portions 90 and 91 to be inserted therethrough and retaining clips 93 are thereafter placed in position to engage notches 94 on the brackets 86 and 87 and thus prevent the removal of these brackets from the top channel 48. At the lower ends of the retaining clips 93 ears 95 are provided. These ears 95 pass through openings 96 in the top channel and are then bent over to prevent their displacement. A pair of springs 97 are mounted on pins 98 and serve to urge the release bars 84 and 85 outwardly and upwardly. The release brackets 88 and 89 at the opposite end of the release bars are identical in construction with the exception that these do not include the operating end portions 90 and 91.

As will be seen from the examination of Fig. 4 and Fig. 7, the operating end portions 90 of the release bar brackets 86 and 87 are positioned directly below the latch trip bracket 78. From this construction it will be seen that any inward force exerted upon the release brackets 84 or 85 will cause them to pivot on the notches 94 of the release bar brackets 86 and 87, this causing the operating end portions 90 to rise and engage the latch trip bracket 78. As hereinbefore explained, this action will release the latch 66 and thus release the pressure from the rolls 30 and 31.

In order that this object may be accomplished automatically in the event of an emergency, an overload slide rod 100 is mounted within the top channel 48 and secured for pivotal movement by means of clips 101 and 102 riveted to the top channel. The end portions of this overload rod are bent as shown in the drawings to provide release triggers 103 and 104 which are positioned directly above the leaf spring 55. It may now be seen that in the event that any object of unusual thickness should come between the rolls 30 and 31, the upper roll 31 will rise against the tension of the leaf spring 55. The leaf spring 55 will then contact one or both of the release triggers 103 and 104 and move them upwardly about the overload slide rod 100 as a pivot. This action will cause the release trigger 104 to bear against the lower surface of the latch trip bracket 78 and release the mechanism as hereinbefore described.

The machine as thus far described will be seen to have several important safety factors, but it is also apparent that it would not be satisfactory for wringing heavy materials of such bulk as to cause material separation between the rolls 30 and 31. For this reason a selector button 105 is mounted in the top of the top channel 48. By reference to Figs. 8 and 9 it will be seen that this selector button includes an enlarged bearing portion 106, passing through the top channel 48 and a saddle 107 eccentrically mounted thereon by means of a screw 108. The saddle 107 engages the release trigger 103 and rotation of the selector button 105 will thus slide the overload slide rod 100 longitudinally and remove the release trigger 104 from its position under the latch trip bracket 78 to the dotted line position indicated at 104^a. When this has been done, it will be apparent that the automatic releasing mechanism will be inoperative since when the spring raises the triggers 103 or 104, the trigger 104 will not engage the latch trip bracket 78, and therefore not cause

a release of the mechanism, and the device will therefore be capable of handling bulky materials. A ball detent 109 is provided in the selector button 105 in order to maintain the parts in the position desired by the operator. It should be noticed that when the overload slide rod has been moved to its inoperative position the rolls 30 and 31 may still be instantly released by operation of the release bars 84 or 85.

In the illustrated embodiment of the invention the release triggers 103 and 104 are so positioned as to contact the leaf spring 55 at points spaced between the plate 51 and the bearings 24 and 26. It will be understood that since the spring 55 has no substantial movement at the center and has its maximum movement at the end portions engaging the bearings 24 and 26, the degree of sensitivity of the device will be determined by the positioning of the triggers 103 and 104 along the spring.

If the triggers 103 and 104 are positioned near the extreme ends of the spring they will be actuated by an extremely small degree of movement between the rolls 30 and 31, but if the triggers 103 and 104 are positioned farther inwardly toward the plate 51, the amount of movement of the roll 31 necessary to effect a release will become correspondingly greater. The positioning of these triggers 103 and 104 may be made adjustable if desired, or they may be fixed in predetermined position at the time of manufacture of the device, as shown in the illustrated embodiment of the invention.

It should also be noted that if the release triggers are positioned at the extreme ends of the spring their operation will not be affected by any adjustment of the spring tension as accomplished by the rotation of the adjusting cap 49 and adjusting plate 51, as hereinbefore described. In the position shown however, any adjustment of the adjusting cap 49 will cause the center portion of the leaf spring to assume a different position, in accordance with the elevation of the notch 54 of the adjusting plate 51. This will vary the initial spacing between the release triggers 103 and 104 slightly, and thus accomplish a manual control of the sensitivity of the automatic release mechanism.

While it is believed that the operation of the device will be apparent from the foregoing description, it will here be briefly reviewed.

When the machine is adjusted to release automatically, any bulky object coming between the rolls 30 and 31 will cause them to separate and cause the leaf spring 55 to contact one or both of the release triggers 103 and 104. The release trigger 104 will then contact the latch trip bracket, release the latch 66 from the latch pin 72, and allow the reset handle 62 to be thrown upwardly by the tension of the leaf spring 55, operating through the reset pivot 63 and through the link 61. Simultaneously, the link 76 will throw the top channel 48 toward the right and release the anchor pin 58 from the notch 59. The rolls 30 and 31 are now completely released and the mechanism must be reset by positioning anchor pin 58 in the notch 59 and manually swinging the release handle 62 downwardly until the latch pin 72 is engaged by the latch 66. If the selector button 105 is in its other position, this automatic operation will not take place and the pressure between the rolls 30 and 31 can be released only by manual operation of the release bars 84 and 85.

While I have illustrated and described what is

at present a preferred embodiment of the invention, it will be appreciated that it is susceptible of embodiment in other wringers and in other forms as well as susceptible of many modifications, all without departing from the invention spirit or the scope of the appended claims.

We claim:

1. In a wringer mechanism including a frame, a plurality of spring-urged pressure rolls and a pressure release mechanism; the combination of a plurality of bearings for the pressure rolls, a flat leaf-spring extending between and adapted to act on said bearings, a spring anchor for said spring, an automatic release control comprising a rod extending longitudinally of said spring and carrying a plurality of triggers adapted to be engaged by said spring to impart rocking motion to said control rod, and a manually operable selector button mounted on the outer surface of the wringer frame and adapted to move said rod between an inoperative position and an operative position wherein the rocking motion imparted by the spring will cause said control rod to engage and actuate the pressure release mechanism of the wringer.
2. In a wringer mechanism including a frame, a plurality of spring-urged pressure rolls and a pressure release mechanism; the combination of a plurality of bearings for the pressure rolls, a flat leaf-spring extending between and adapted to act on said bearings, a spring anchor for said spring, an automatic release control extending longitudinally of said spring within said wringer frame and adapted to be engaged by said spring at one of a plurality of points to impart motion to said control, and a manually operable selector mounted on the outer surface of the wringer frame and adapted to move said control between an inoperative position and an operative position wherein the motion imparted by the spring will cause said control to engage and actuate the pressure release mechanism of the wringer.
3. In a wringer, a lower frame, a pair of cooperating rolls, spring means to urge said rolls into pressure relationship, an upper frame including a top surface and downwardly extending flanges adapted to constitute a housing for said spring; locking means to secure said upper frame to said lower frame; a release means for said lock, and manually operable controls to actuate said release; an automatic release control rod extending longitudinally within said frame and in parallel-spaced relationship with said spring, and adapted to be actuated by said spring whenever said spring flexes beyond a predetermined point; means operatively interconnecting said automatic control rod with said locking means

whereby the aforementioned locking means may be released responsive to movement of the control rod; and a manually operable selector control comprising a button extending outside of said top frame whereby the operative interconnection between said automatic control rod and said locking means may be disengaged to render said control rod inoperative.

4. In a wringer, a lower frame, a pair of cooperating rolls, spring means to urge said rolls into pressure relationship, an upper frame including a top surface and downwardly extending flanges adapted to constitute a housing for said spring; locking means to secure said upper frame to said lower frame; a release means for said lock, and manually operable controls to actuate said release; an automatic release control member extending longitudinally within said frame and in parallel-spaced relationship with said spring, and adapted to be actuated by said spring whenever said spring flexes beyond a predetermined point; means operatively interconnecting said automatic control member with said locking means whereby the aforementioned locking means may be released responsive to movement of the control member; and a manually operable selector control extending outside of said top frame whereby the operative interconnection between said automatic control member and said locking means may be disengaged to render said control member inoperative.

5. In a wringer, a pair of cooperating rolls, spring means to urge said rolls into pressure relationship, a frame including a top and side surfaces adapted to completely enclose and constitute a housing for said spring; locking means to secure said rolls in pressure engagement; a release means for said lock, and manually operable controls to actuate said release; an automatic release control member extending longitudinally within said frame and in parallel-spaced relationship with said spring, and including trigger portions adapted to be actuated by said spring whenever said spring flexes beyond a predetermined point; means operatively interconnecting said automatic control member with said locking means whereby the aforementioned locking means may be released responsive to movement of the control member; and a manually operable selector control comprising a button extending outside of said frame whereby the operative interconnection between said automatic control member and said locking means may be disengaged to render said control member inoperative.

NICHOLAS L. ETTEM.
ADOLPH J. SNOW.
